ROY D. MAILEY, OF EAST ORANGE, NEW JERSEY, ASSIGNOR TO COOPER HEWITT ELECTRIC COMPANY, OF HOBOKEN, NEW JERSEY, A CORPORATION OF NEW JERSEY.

MERCURY SWITCH.

Application filed October 10, 1923. Serial No. 667,625.

To all whom it may concern:

Be it known that I, Roy D. Mailey, a citizen of the United States, and resident of East Orange, county of Essex, State of New Jersey, have invented certain new and useful Improvements in Mercury Switches, of which the following is a specification.

This invention relates to switches of the type in which mercury is used to make and break connection between electrical conductors.

Up to the present considerable trouble has been experienced with switches having containers of glass of high coefficient of expansion and low melting point due to the breaking of the glass of the container either at the point of rupture of the electrical connection or at or near the seal-in due to electrical conditions within the switch.

This trouble is particularly heavy in such switches when they are used in inductive circuits due to the high voltage arc induced at the breaking of the circuit and the consequent rapid changes of temperatures produced within the switch tube. The change in temperature thus brought about is over an enormously wide range and occurs in an exceedingly short period of time and has an excessively destructive effect on glass ordinarily used in this type of switch. The comparatively rapid change again from the high to the low temperatures also has its deteriorating effect upon the glass.

As a consequence of these high temperatures and rapid temperature changes over wide ranges the glass in ordinary switches of this type is eroded and eaten away with an attending weakening of the glass and a setting up of excessive strains therein. The ultimate result of these conditions is that the glass breaks at the points in area of erosion or at the points and areas of juncture of said wells with the tube proper. There are, of course, natural strains in the walls of the tube itself and at its juncture with the wells which are either released with a consequent breaking of the tube or are augmented by the new strains with a similar result.

The destructive effect due to the temperature changes consequent on the high voltage arcs of inductive circuits is likewise produced in such switches in circuits which are

subject to high current surges. Such circuits are, for example, lamp circuits having heavy loads such as the lamp banks of advertising signs and such as stereopticon lamps. The initial, or cold, resistance of the lamps used in such cases is so much less than that of the lighted and hot lamps that when the circuits to them is first closed there is a rush of high current flow which is checked only by the increased resistance of the lamps which occurs when their temperature rises. The current flowing during this rush is so high that in the aforesaid mercury tube type of switch rapid temperature changes over a wide range occur with the same destructive effect upon the glass of the switch that attends switches in inductive circuits as hereinbefore described.

As an example it is noted that in a stereopticon lamp circuit normally operating at 1,000 watts and 110 volts there is such a difference between the hot and cold resistances of the lamp that in the current surge when the circuit switch is first closed that the current attains a value as high as 110 amperes. It is this starting current that determines the life of the switch in such cases and mercury tube switches above referred to as ordinarily made are quickly deteriorated and destroyed through the rapid and high temperature changes produced by it.

It is the purpose of this invention to provide a switch of mercury tube type which will withstand and is substantially unaffected by rapid temperature changes over wide ranges.

It is further a purpose of this invention to provide a switch of this type in which excessive temperatures are inhibited.

In the drawings Fig. 1 is a side view of a switch in which the glass used is G702P glass.

Fig. 2 is a similar view of a switch of pyrex glass with G702P glass at the seal-ins of the terminals, the latter indicated by cross sectioning.

Fig. 3 is a similar view of a switch of fused quartz with a graded glass seal-in as indicated by sectioning.

Fig. 4 is a detail view of a seal-in in which the different glasses used are indicated by different cross sectioning.

To obtain a switch that will withstand

high voltage kicks as well as high current surges with their consequent high temperatures I use for the switch tube glass that is peculiarly adapted to withstand high temperatures and rapid fluctuations in temperatures over wide ranges, and, when desired in combination with a gas in said tube such as hydrogen, which will assist in the dissipation of heat from the switch, the metal of the terminals being themselves tolerably good conductors of heat.

In some of my switches I use a boro-silicate glass containing an appreciable amount of lead. This glass is generally known in the arts and in the trade as G702P glass. It has a thermal coefficient of expansion near to that of tungsten which latter I use for the terminal seal-in of the switch. This glass I find has arc resisting qualities of a much higher order than ordinary glass used for this purpose.

For switches which are subjected to much harder usage I use a boro-silicate glass containing an appreciable amount of aluminum for the body of the switch tube, with the G702P glass at the seal-ins of the switch terminals. This glass is known generally in the arts and in the trade as pyrex or pyrex glass. It withstands heat and sudden temperature changes over wide ranges to a marked degree and I have found that in a switch of the mercury tube type that its combination with the mercury of the switch, the tungsten of the seal-in, and hydrogen gas with which I fill my switches results in an object long desired in the switch art but not before obtained, namely—a mercury tube switch which withstands the erosive action to which the inner surface of the switch is subjected during the making and breaking of the circuit through the switch as hereinbefore recited.

In the G702P glass switch as shown in Fig. 1 the combination of the glass, the mercury, the tungsten terminals and the hydrogen gas with which I fill the switches results in a sufficient dissipation of the heat from current surges or voltage kicks and are to enable the switch to withstand such conditions up to extreme cases. The pyrex switch combination results in a switch which withstands even extreme cases of hard usage over extended periods of time.

Another switch I have invented is a combination of mercury, hydrogen, tungsten terminals, fused quartz switch tube and a graded seal between the fused quartz and the seal-in of the terminals. This switch withstands extremely hard usage over extended periods of time and is used in places where the pyrex switch can not be used and in other places to which it is peculiarly adapted. The fused quartz of the body of the tube withstands the most extreme hardships that switching conditions can impose on switches.

Fig. 1 of the drawings shows an envelope 1 of boro-silicate glass containing an appreciable amount of lead and generally known in the arts and trade as G702P glass. Formed in the wall of said envelope are the wells 4 of the same glass and which have sealed therethrough at thickened portions the tungsten terminals 3. Within the envelope is a quantity of mercury 2 sufficient to fill the wells 4 and to span the space between them. Before the envelope is sealed off it is cleared of deleterious gases and filled with hydrogen.

Fig. 2 shows a switch tube of which the envelope 5 is made of a boro-silicate glass containing an appreciable amount of aluminum and generally known in the arts and trade as pyrex glass. In this switch tube the wells 6 are made of the G702P glass above mentioned and described. This form has the advantages of the pyrex glass with its resistance to the destructive erosive action of high temperatures, sudden changes of temperature over wide ranges, and the cutting effect of high temperature arcs. The seal or fusion of the G702P glass of the wells to the pyrex glass of the envelope wall is made at a place removed from that at which disruption takes place between the main body of mercury and the mercury of the wells at the breaking of the circuit through the switch, so as to flood the seal area with mercury at this moment, thus protecting the joints and other less resistant portions of the container walls.

Fig. 3 shows a switch tube with an envelope 7 of fused quartz glass. The tungsten terminals are sealed through G702P glass at the bottom of the wells 8. Between the terminal seal-in there is a graded seal 9 of intermediate glasses as indicated in Figure 4.

From what has been said above by way of illustration of my invention, it will be apparent to one skilled in the art that exhausted or gas filled switches may be made from quartz with graded glass seals running down to tungsten, or further down to platinum, or to the duplex metals known in the art as dumet, and the like; that the envelope 1 may be made of any glass having a coefficient of thermal expansion in the neighborhood of that of quartz, such as the ones mentioned herein either as container material, or as material of the step seals of the various embodiments. I have found that tungsten meets the requirements of the seal structure exceptionally well but regard any of its analogues in the tungsten group as coming within the scope of my invention.

The subject matter relating to the tungsten and like electrodes is covered more fully in the specification and claims of applicant's copending application Serial No. 720,697, filed June 17, 1924, mercury switch.

It is, of course, well known that devices of this type are tilted or rotated to make and break the connection between the pools 4, 4, in the making and breaking of a circuit 5 through the switch.

I claim as my invention:

1. In a mercury tube switch, in combination, an envelope of boro-silicate glass carrying an appreciable quantity of lead and contacts sealed into the walls of said envelope, said envelope being filled with a gas having the property of assisting in removing heat from the high temperature points in the envelope. 10
2. In a mercury tube switch, in combination, an envelope of boro-silicate glass carrying an appreciable amount of lead and contacts sealed into the walls of said envelope, said envelope being filled with hydrogen. 15
3. In a mercury switch of the electrode pool type, in combination, an envelope of boro-silicate glass carrying an appreciable amount of lead, wells communicating with the chamber formed by said envelope and sealed to the walls proper of said envelope, the sealing being made at a point remote from the place of make and break of the pools and the main body of mercury, and tungsten electrodes sealed into said wells, 20 said envelope being filled with hydrogen. 30
4. In a mercury tube switch, in combination, an envelope of glass having a coefficient of thermal expansion substantially that of boro-silicate glass and greater than that of fused silica, contacts sealed into the walls of said envelope, and a contact making and breaking member in said envelope for bridging the gap between said contacts. 35
5. In a mercury tube switch, in combination, an envelope of glass having a coefficient of thermal expansion substantially that of boro-silicate glass and greater than that of fused silica, contacts sealed into the walls of said envelope, and a gas assisting in removing heat from said envelope. 40
6. In a mercury switch, in combination, an envelope of glass having the property of withstanding high temperatures and rapid fluctuations in temperature and a well formed thereon of boro-silicate glass, mercury in said switch, and lead wires passing through the wall of the envelope and in contact with said mercury. 50
7. In a mercury switch, in combination, an envelope of glass having the property of withstanding high temperatures and rapid fluctuations in temperature and wells formed thereon of boro-silicate glass, mercury in said switch, and lead wires passing through the wall of the envelope and in contact with said mercury. 55
8. In a mercury switch, in combination, an envelope of glass containing an appreciable quantity of metal and having the property of withstanding high temperatures 60
9. In a mercury switch, in combination, an envelope of glass containing an appreciable quantity of metal and having the property of withstanding high temperatures and rapid fluctuations in temperature, mercury pools in said envelope in the open position of said switch, and lead wires passing through the wall of the envelope and in contact with said pools. 70
10. In a mercury switch, in combination, an envelope of glass carrying an appreciable quantity of metal, wells opening into said envelope, and contacts sealed into the walls of said envelope and terminating in said wells. 75
11. In a mercury switch, in combination, an envelope of boro-silicate glass carrying an appreciable quantity of metal, a well opening into said envelope, and dividing the mercury into two pools in the open position of the switch, and contacts passing through the wall of the switch and terminating in said pools. 80
12. In a mercury switch, in combination, an envelope of boro-silicate glass carrying an appreciable quantity of metal, mercury pools in said switch, and tungsten lead in wires sealed in the wall of the envelope and in contact with said mercury pools. 85
13. In a mercury switch, in combination, an envelope of boro-silicate glass carrying an appreciable quantity of metal, mercury pools in said envelope in the open position of said switch, and a gas in said envelope having the property of assisting in the removal of heat from the high temperature points in the envelope. 90
14. In a mercury switch, in combination, an envelope of boro-silicate glass carrying an appreciable quantity of metal, mercury pools in said envelope in the open position of said switch, tungsten lead in wires sealed in the wall of the envelope and in contact with said mercury pools, and a gas in said envelope having the property of assisting in the removal of heat from the high temperature points in the envelope. 95
15. In a mercury switch, in combination, an envelope of boro-silicate glass, contacts sealed through the walls thereof, and mercury therein. 100
16. In a mercury switch, in combination, an envelope of boro-silicate glass, contacts sealed to said boro-silicate glass through a graded boro-silicate glass seal, and a quantity of mercury in said envelope. 105
17. In a mercury switch, in combination, an envelope of boro-silicate glass having wells opening thereinto, contacts sealed through the wall of said envelope and ter- 110
18. In a mercury switch, in combination, an envelope of boro-silicate glass having wells opening thereinto, contacts sealed through the wall of said envelope and ter- 115
19. In a mercury switch, in combination, an envelope of boro-silicate glass having wells opening thereinto, contacts sealed through the wall of said envelope and ter- 120
20. In a mercury switch, in combination, an envelope of boro-silicate glass having wells opening thereinto, contacts sealed through the wall of said envelope and ter- 125
21. In a mercury switch, in combination, an envelope of boro-silicate glass having wells opening thereinto, contacts sealed through the wall of said envelope and ter- 130

minating in said wells, and a body of mercury in said envelope.

18. In a mercury switch, in combination, an envelope of boro-silicate glass having wells opening thereinto, contacts sealed through the wall of said envelope in said wells through a graded boro-silicate seal and terminating in said wells, and a body of mercury in said envelope.
- 10 19. In a mercury switch, in combination, an envelope of glass having the property of withstanding high temperatures and rapid fluctuations in temperature, mercury pools in said envelope in the open circuit position of said switch and lead wires in contact with said pools passing through the wall of the

envelope in sealed relation to boro-silicate glass carried by said well.

20. In a mercury switch, in combination, an envelope of glass having the property of ²⁰ withstanding high temperatures and rapid fluctuation in temperature, mercury in said envelope, and lead wires passing through the wall of the envelope in sealed relation to boro-silicate glass carried by said envelope ²⁵ and being in contact with said mercury in a closed circuit position of the switch.

Signed at Hoboken in the county of Hudson and State of New Jersey this 9th day of October A. D. 1923.

ROY D. MAILEY.
